Attorney

UNITED STATES PATENT OFFICE.

AUGUST SPEIDEL, OF OMAHA, NEBRASKA.

SELF-OILING SWING HOOK.

Application filed July 6, 1926. Serial No. 120,737.

This invention relates to improvements in hooks for use with porch and outdoor swings and for similar purposes.

Swings of all types are usually suspended from a stationary support to which they are connected by means of chains. The upper end of the chain is connected to the stationary support by means of two interengaging eyelets. As the swing oscillates the adjacent surfaces of the eyelets move against each other and as it is impossible to lubricate these surfaces with the present arrangement of hooks, they wear very fast and besides they always become noisy, producing loud and unpleasant squeaks which are highly objectionable.

It is the object of this invention to produce a construction of hook for use with swings which permits the moving parts to be properly lubricated at all times, thereby increasing the life of the hook and preventing disturbance due to the squeaking of the parts.

My invention briefly described consists in surrounding the relatively movable supporting surfaces by means of a basin, pan or other retainer which is adapted to contain a supply of oil, which serves to keep the relatively movable surfaces properly lubricated at all times.

My invention can be best understood and most clearly described when reference is had to the accompanying drawing in which it has been illustrated, and in which:

Figure 1 shows a perspective view of one form of my invention, a part being broken away to better disclose the construction;

Figure 2 is a section taken on line 2—2, Figure 1; and shows the parts in normal position by means of full lines while one of the extreme positions is indicated by dot and dash lines;

Figure 3 is a section similar to that shown in Figure 2, but with the cap removed and a ball point provided instead of the sharp point employed in the embodiments illustrated in Figures 1 and 2;

Figure 4 is a section taken on line 4—4, Figure 5, and shows a slightly modified form of the hook illustrated in Figures 1 and 2;

Figure 5 is a section taken on line 5—5, Figure 4;

Figure 6 is a section similar to that shown

in Figure 5 but showing the parts in the 55 extreme position;

Figure 7 is a section of a modified form of the invention in which the movable members are composed of two interconnected eyelets, the parts being shown in normal position; 60 and

Figure 8 is a section similar to that shown in Figure 7 but with the parts in extreme abnormal position.

Numeral 1 indicates the shank part of the 65 upper or stationary member. This shank is adapted to be passed through an opening in a supporting member which has not been shown. The lower part of portion 1 is bent somewhat as shown in Figure 2 where it 70 forms a substantially closed loop having side members 2, 3, 4 and 5, opposite sides of which are substantially parallel. The member 5 being somewhat shorter than the opposite member 3 so as to leave a gap 6 75 through which the movable member 7 can be inserted into operative position. Located within the loop above referred to and supported from the inner surfaces of the sides 80 3 and 4 is a basin or pan 8, which is preferably of pyramidal shape and which is fastened to the supporting sides by means of solder or by being autogenously welded in place. The sides 9 and 10 of the pan 8 85 have upwardly extending inwardly curved portions 11, whose function will hereinafter appear. The movable member, which has been indicated as a whole by numeral 7, is somewhat heart-shaped and has divergent 90 side members 12 whose upper ends are curved and integrally connected to the downwardly extending tapering member 13 whose lower end rests in the apex of the pan 8 in the manner shown in Figure 2. The lower end of the member 7 is formed 95 into a loop 14 to which the upper link 15 of the chain is connected. When the parts are assembled in the manner shown in Figure 2, the chain may be oscillated through an angle of approximately forty-five degrees from the vertical. At this angular 100 displacement the parts will assume the position shown in dot and dash lines. Of course, the parts may swing an equal angular distance to the other side of the vertical, 105 thereby making a total angular displacement of approximately ninety degrees. The cavity within the pan 8 is intended to be filled

with a lubricating oil so that the movable surface of the point 13 will always be separated from the surface of the pan by a film of oil. It is, of course, evident that if the 5 supporting hook is exposed to the weather, that water would find its way into the pan whenever it rained, and since oil is of a smaller specific gravity than water, the water would naturally displace the oil. In 10 order to protect against the entry of water into the pan, I have provided a cover 16 which is so constructed that it can readily be put into place over the pan, and whose edges are spaced from the pan a sufficient distance 15 to permit the member 7 to move freely in the direction indicated in Figure 2.

In Figure 3 I have shown a cross section 20 which is taken in a plane perpendicular to the plane of the loop formed by sides 2, 3, 4 and 5. In this modified form the downwardly projecting point 13^a, which corresponds to member 13 in Figure 2, is provided with a spherical point 17 and the bottom of the pan 8^a is curved so as to conform to the 25 curvature of the point 17. The upper edges of opposite sides of pan 8^a are bent inwardly in the manner indicated by reference 30 numeral 18. Metal plates 19 are secured to the inner surfaces of the opposite sides of pan 8^a by means of screws 20. These plates 19 are intended to prevent the upward movement of the heart-shaped member 7^a by reason of their lower edges forming an abutment 35 which prevents the spherical part 17 from being moved upwardly. Although in Figure 3 I have not shown the cover 16, this is intended to be applied in the same manner as shown in Figures 1 and 2.

It is evident that with the parts constructed 40 in the manner shown in Figures 1, 2 and 3, the swinging of the chain 15 is limited to an angle of approximately ninety degrees. This may be sufficient for porch swings and swings located indoors, but it is 45 not considered sufficient for outdoor swings such as used on school playgrounds or in the parks. It is, of course, possible to move the chain through a greater angle than the angle to which the member 7 can move, for the 50 reason that after the member 7 has reached the dotted line position, in Figure 2, the upper link 15 of the chain will move with respect to the loop 14 which then becomes the pivot point about which the swing oscillates. Where a greater arc than ninety 55 degrees is contemplated, it is preferable to change the design of the supporting members to a slight degree so that they may have an oscillating movement of substantially one hundred eighty degrees with respect to each other. Such a construction 60 has been shown in Figures 4, 5 and 6 which will now be described.

The upper part of the supporting member 65 illustrated in Figure 4 differs slightly from

the corresponding part shown in Figures 1, 2 and 3 and instead of having four sides which form practically a square, this member is provided with six sides which have been numbered consecutively from 21 to 26. 70 The sides 22 and 25 are parallel with each other, while 23 and 24 form an acute angle and serve as supports for the pan or basin 27. The cover 28 which corresponds to the cover 16 in Figure 1 has a somewhat semi-circular shape like that indicated in Figure 5. The lower part of the supporting hook which corresponds to 7 and 7^a in Figures 1 and 3, respectively, has been indicated as a whole by reference numeral 7^b and has the same general shape. The sides 29 and 30 75 form an obtuse angle and are connected by an arcuate portion 31 from the center of which the supporting pin 32 extends downwardly in the direction of the shank 33. When the parts are in normal position, the pin 32 rests in the lowermost portion of the pan 27 in the manner shown in Figures 4 and 5. This permits the parts 7^b to oscillate in its own plane about the point of the pin 32 from the full line position to the dotted line position shown in Figure 5. It is evident from Figure 5 that when the pin 32 reaches a dotted line position, the member 7^b cannot oscillate farther about the end of the pin and therefore any further oscillation will take place about the point 34 where the angle between the arcuate portion 31 and the pin 32 engages the upper edge of the pan 27. The member 17 can continue to oscillate about this pivot point until it assumes the position shown in Figure 6 and therefore the shank 33 can move through an arc of one hundred eighty degrees, which is considered sufficient for outdoor swings. It 85 will be noticed that with the construction shown in Figures 4, 5 and 6, the point of oscillation for the member 7^b changes during the ninety degrees swing from neutral to extreme position.

In Figures 7 and 8 I have shown a slightly modified form of my invention, in which the upper part of the supporting hook, which I have here designated by numeral 35 is provided at its lower end with an eyelet 36 of substantially elliptical shape, having its major axis perpendicular to the axis of the shank 35. The lower part of the supporting member has been indicated as a whole by reference numeral 37 and is provided at its upper end with an eyelet 38 which engages in the eyelet 36 in the manner clearly shown. The lower end of part 37 has an eyelet 39 to which the upper link 15 of the chain is connected. A dish-shaped cover member 40 is provided with a central opening through which the shank 35 is extended and may be secured to the latter by being soldered at point 41. It is evident that the two parts 35 and 37 may have a swinging motion with 90 95 100 105 110 115 120 125 130

respect to each other and that the arc through which the member 37 can swing is only limited by the bottom flange of the cover 40. Attention is called to the fact that 5 the loop 36 is much larger than the diameter of the material forming the eyelet 38 so that the latter can have a sliding motion with respect to the eyelet 36. When the member 37 is in normal position, it will be 10 supported by the eyelet 36 at a point directly beneath the axis of member 35, but as the swing moves outwardly to the limiting position shown in Figure 8, the point about which the member 37 swings will gradually 15 move to the point shown in Figure 8. The object in this construction is to provide room for the lubricant containing pan 42, which is secured to the member 37 somewhat as shown in Figures 7 and 8. This pan has a 20 downwardly projecting part 43 that is soldered to the part 37 so as to prevent leakage. The bottom of pan 42 is upwardly inclined and terminates in an upwardly and inwardly inclined flange 44. A conical re-enforcing member 45 has been shown and this extends from the projection 43 to the outer edge of the bottom of the pan. It is evident that this reenforcing member may be dispensed with if desired. It is necessary 25 that the lubricant shall always be at a level slightly higher than the point of contact between the eyelets 36 and 38 and at the same time it is desirable to permit the parts to swing through an arc of one hundred eighty 30 degrees. This has been made possible by making the eyelet 36 elliptical so that in moving from the position shown in Figure 7 to that of the position shown in Figure 8, the point about which the pivoting occurs will 35 move sufficiently to prevent the upper edge of the pan from striking the shank 35. If the parts were to remain stationary for any length of time in the position shown in Figure 8, it is evident that the only lubricant 40 that would remain would be that which is contained in the shaded area 46 in Figure 8, but in the first place the parts only remain in this position for a very short time which does not give the oil or lubricant time to flow 45 out, and in the second place it is contemplated to fill the space about the eyelets with waste or other absorbent material which will prevent the free flow of the lubricant, and at the same time permit the surfaces to 50 be properly lubricated.

If the member 7 is oscillated to such an extent that the end of the pin 13 comes up over the top of the pan 8, the curved end 11 will prevent the part 7 from moving transversely 55 and will direct it downwardly into the pan.

I wish to call attention to the common idea that is shown in all of the modifications illustrated. This idea broadly described consists in forming the supporting member of two

relatively movable parts and attaching to one 65 part a lubricant container which is adapted to contain sufficient lubricant to keep the point of contact between the two members submerged therein, and to provide a cover member which will exclude rain from entering 70 the lubricant pan. The cover member is made necessary by the fact that oil has a smaller specific gravity than water and therefore would be gradually displaced by 75 water if the latter could enter the pan.

Having now described the invention what is claimed as new is:

1. A hook having an upper part provided with means for attaching it to a support, a lower part having its lower end provided with 80 means for making connection with a swing, said parts having cooperating surfaces which prevent longitudinal separation while permitting relative swinging movement, a pan secured to one of said members, said pan having a downward depression adapted to contain a lubricant and having its upper edge extending above the level of the cooperating surfaces so that the level of the lubricant may 85 extend over the contacting surface and an upwardly convex cover attached to the upper part for shielding the pan so that water cannot enter from above, said cover member being of such size that its outer periphery 90 extends beyond the edges of the pan.

2. A two part hook for supporting a swing member, one of said parts having means for securing it to an elevated stationary support and the other having means for securing it to a swing, a pivotal connection between said parts comprising a lubricant pan of pyramidal shape attached to one of said parts and whose sides extend upwardly from a central apex forming a bearing for the other part which is provided with a depending member engaging said apex so as to give the lower part room to automatically adjust itself laterally, in case the upper part should be out of line with the lower, this lateral adjustment taking place inside of the lubricant 100 pan.

3. A hook having upper and lower parts adapted for use in suspending a swing from a stationary support, a pivotal connection between said parts comprising a lubricant pan of pyramidal shape attached to one of said parts and whose sides extend upwardly from a central apex forming a bearing for the other part which is provided with a depending member engaging said apex, and a cover member held and fastened to the upper part above said pan and extending over and down around the pan so as to leave ample room for said parts to move freely under and without said cover and protect the pan and parts 110 well from moisture and water.

In testimony whereof I affix my signature.
AUGUST SPEIDEL.
